UNITED STATES PATENT OFFICE

JAY A. HEIDBRINK, OF MINNEAPOLIS, MINNESOTA

ANÆSTHETIZING APPARATUS

Application filed June 5, 1928. Serial No. 283,015.

My invention relates to anæsthetizing apparatus, and an object in general is to provide an improved apparatus for delivering gases to be used as an anæsthetic. An object in particular is to provide means whereby a plurality of gases, such as nitrous oxid and oxygen may be readily delivered from independent sources of supply in the following different ways:

1. A properly proportioned nitrous oxid-oxygen mixture may be delivered to an inhaler and to a gas bag.
2. A properly proportioned nitrous oxid-oxygen mixture may be delivered to the inhaler without any of the mixture passing to the gas bag.
3. Nitrous oxid alone may be delivered to the inhaler and to the gas bag.
4. Nitrous oxid alone may be delivered to the inhaler without any of it passing to the gas bag.
5. Oxygen alone may be delivered to the inhaler and to the gas bag.
6. Oxygen alone may be delivered to the inhaler without any of it passing to the gas bag.

Another object is to provide means for delivering gases in the above mentioned ways in combination with means for controlling and registering the pressure under which the gases are delivered.

The full objects and advantages of my invention will appear in connection with the detailed description thereof, and the novel features of my inventive idea will be particularly pointed out in the claims.

In the accompanying drawings which illustrate a practical embodiment of my invention,

- Fig. 1 is a top plan view of an anæsthetizing apparatus provided with my invention.
- Fig. 2 is a view in vertical section on the line 2—2 of Fig. 1.
- Fig. 3 is a view in vertical section on the line 3—3 of Fig. 1.
- Fig. 4 is a view in vertical section on the line 4—4 of Fig. 1 on an enlarged scale.
- Fig. 5 is a view in horizontal section on the line 5—5 of Fig. 4 showing a cam device in normal operating position.
- Fig. 6 is a fragmentary view similar to a portion of Fig. 5 showing

the cam device moved into another position. Figs. 7, 8, and 9 are fragmentary views in horizontal section showing the cam device moved into still different positions. Fig. 10 is a view in vertical section on the line 10—10 of Fig. 5. Fig. 11 is a view in vertical section on the line 11—11 of Fig. 6.

As shown in the drawings with reference particularly to Fig. 2, there is a casting 12 which is provided with a socket 14 in its lower portion for receiving the upper end of a supporting standard 16. Two arms 18 and 20 extend out from opposite sides of the casting 12. Enlarged central portions 22 and 24 of cross bars 26 and 28 are secured to the ends of the arms 18 and 20 respectively. The ends of the cross bar 26 are provided with yokes 30 and 31 within which the heads of gas containers are adapted to be secured by screws 32 and 33. The gas containers on this side of the machine are intended particularly for containing oxygen. The ends of the cross bar 28 are provided with yokes 34 and 35 within which the heads of gas containers are adapted to be secured by screws 36 and 38. The gas containers on this side of the machine are intended particularly for holding nitrous oxid and one of them is designated by the numeral 40 in Fig. 3.

Each of the cross arms 26 and 28 contains a passageway 42 as shown in Fig. 3 with which the gas containers are adapted to be placed in communication respectively by means of needle valves 44. Since the two sides of the apparatus are alike in regard to the control of the supply of nitrous oxid and oxygen from the gas containers, a detailed description of one side may be considered as applicable also to the other side. Each end of the passageway 42 may be closed by means of a plug 46 when a gas container is not attached to such end. As will be seen from Fig. 2, the passageway 42 is provided with a pressure controlling device which includes an upwardly extended cap 47 screwed upon the upper dished side of the central enlarged portions 22 and 24 of the cross arms, the enlarged portions having downwardly extending tubular members 48 closed at the bottom by plugs 49. Within the tubular

member 48, there is a sliding block 50 which carries a fiber plug 51 on its upper side, this plug being adapted to engage the outlet end of a hole 52 extending down from the passageway 42. The block 50 is held upwardly by a spring 54 and may be depressed by means of a staplelike member 56, the upper end of which is engaged by the lower surface of a diaphragm 58 extending across the 5 dished upper end of the member 22 so that a chamber 60 is formed below the diaphragm. This chamber as shown in Fig. 2 is provided with a safety valve 61. A spring 62 rests upon the upper surface of the diaphragm 58 10 and the tension of this spring may be regulated by a screw 63 threaded through the upper portion of the cap 47.

From the chamber 60, the gas passes through a tube 64 to a valve head device 66, 20 this tube also being connected by a branch tube 68 to a pressure gauge 70. As before stated, the controlling mechanisms are the same for both sides of the apparatus and hence there are two gauges 70, one for oxygen 25 and the other for nitrous oxid. The valve head device 66 is secured over a mixing chamber 72 formed in the upper portion of the casting 12. As shown in Fig. 2, the tubes 64 lead into the valve head device which has 30 an aperture 74 for passage of oxygen and an aperture 76 for passage of nitrous oxid, the latter aperture being considerably larger than the former. It will be understood that by properly proportioning these apertures, 35 the percentages of gases in the mixture may be determined. The passage of gases through these apertures into the mixing chamber is brought about or stopped at will be means of a disk valve 78 which is secured to the lower 40 end of a stem 80 which is slidably mounted in the head. The upper end of the stem 80 as shown in Fig. 2 is threaded to receive a thumb nut 82 which may be turned so as to cause the valve 78 to close the apertures or to 45 open them to the desired extent as indicated by a pointer 83 cooperating with graduation marks on top of the head 66 as shown in Fig. 1. As shown in Fig. 4, springs 84 interposed between the head 66 and the valve 78 serve 50 to hold the latter open to the extent which is permitted by the position of the nut 82 while a pin 85 prevents the stem 80 from turning in the head.

The forward portion of the casting 12 is 55 formed into an enlarged hollow member 86. A passageway between the mixing chamber 72 and the interior of the hollow member 86 is controlled by a valve 88 having a stem 90 extending through a guide 91 and part way 60 into the member 86. A coiled spring 92 engaging the valve 88 and surrounding a cylindrical rearward extension 93 thereof serves to normally hold this valve closed. The extension 93 is provided with perforations 65 95 for passage of gas.

The two gas chambers 60 are respectively connected by tubes 94 and 96 with tubular extensions 98 and 100 extending out from opposite sides of the member 86. The passageway through the extension is controlled by a valve 102 having a stem 104 extending through a guide 105 and part way into the member 86. A coiled spring 106 engaging the valve 102 serves to normally hold it closed. The passageway through the extension 100 is controlled by a valve 108 having a stem 110 extending through a guide 111 and part way into the member 86. A coiled spring 112 engaging the valve 108 serves to normally hold it closed.

As shown in Figs. 10 and 11, the member 86 is provided with a downward tubular extension 114, the lower end of which is externally threaded to receive internal threads formed in the upper end of a coupling 116 to the lower end of which a reservoir bag 118 is attached, serving for breathing and re-breathing and hereafter referred to as a gas bag. Within the coupling 116 there is a valve seat 120 with which a valve 122 is adapted to cooperate. This valve has a downwardly extending stem 124 which is slidable in a tubular projection 126 extending up from the cross bar 128 carried by the lower end of the coupling 116. A coiled spring 130 surrounding the stem 124 and interposed between the projection 126 and the lower side of the valve 122 tends to normally hold the valve in open position. A short stem 132 which may be a continuation of the lower stem 124 extends up from the valve 122, the lower portion of the stem 132 being provided with a shoulder 134. A tubular member 136 is slidably mounted on the stem 132, the member 136 merging into a pin 138 at the lower end of which there is a shoulder 140. The pin 138 is slidable in an arm 141 carried by the tubular member 86. A coiled spring 142 is interposed between the valve 122 and the shoulder 140, this spring being stiffer than the spring 130. The provision of the spring 142 insures closing of the valve 122 when the pin 138 is pushed without liability of the pin becoming jammed and also takes care of wear on the pin so that regardless of wear, the valve will always be firmly seated when the spring 142 is compressed.

The hollow member 86 is provided with a cover 144 which has a central bearing and packing gland 146 as shown in Fig. 4 for a rotatable shank 148 which at its upper end carries a handle 150 and at an intermediate place carries a pointer 152 which just clears a disk 154 carried by the cover 144. The disk 154 as shown in Fig. 1 is provided with six marks disposed around its periphery and indicated at *a*, *b*, *c*, *d*, *e*, and *f*, the mark *c* in this figure being covered by the pointer 152 and the handle 150 which is located above the 120 125 130

same. The shank 148 at its lower end carries a cam device designated in general by the numeral 156. This cam device at its upper end is provided with a peripheral cam surface 158 adapted when properly positioned to push rearwardly on the valve stem 90 of the valve 88 which controls the supply of the mixed gases from the mixing chamber. It will be noted from Figs. 4 and 11 that 5 the stem 90 is mounted at a slightly higher level than the stems 104 and 110, these latter stems being at a common level. The cam device just below the cam surface 158 is provided with a second peripheral cam surface 160 adapted to cooperate with either the stem 104 or the stem 110 but only one of them at a time and furthermore only when the cam surface 158 is not engaged with the stem 90. The cam device is capable of 10 rotative movement between the marks *a* and *f* on the longer arc connecting these marks. The cam device on its lower end has three downwardly extending cam surfaces 162, 164 and 166 spaced from each other circumferentially and anyone of which is adapted to engage the pin 138 during different rotative positions of the cam device for depressing the valve 122 against the tension of the spring 130 so as to close communication with 15 the gas bag 118.

Extending forwardly from the hollow member 86, there is a tubular projection 168 adapted to be connected by a tube 170 with an inhaler of well known construction such 20 as a nasal inhaler. Also extending out from the member 86 there is a tubular projection 172 adapted to be connected by a tube with another inhaler of well known construction such as a mouth inhaler. The projection 172 25 is provided with a shutoff cock 174 which when closed prevents passage of gas through this projection. Also connected with the member 86, there is a safety valve device 176. As will be apparent from Fig. 7, this device 30 includes a disk 178 resiliently held upon its seat by a spring 180, the tension of which may be varied by turning a screw cap 182.

With the foregoing description of the 35 details of construction in mind, the operation 50 of the apparatus and especially of the cam device and valves operated thereby will be readily understood. When the rotatable cam device is in the position shown in Figs. 5 and 10, with the pointer 152 in register with the mark *c* which is the position of the pointer in Fig. 1, the cam surface 158 opens the valve 88 so that a mixture of two gases such as oxygen and nitrous oxide will pass from the mixing chamber into the hollow member 60 86 and out to the inhaler, the valves 102 and 108 now being closed. At the same time, the mixture is permitted to pass into the gas bag 118 since the cam surface 164 is off the pin 138 as shown in Fig. 10 so that the valve 122 65 is held open by the spring 130. When the cam device is turned to bring the pointer 152 into register with the mark *d*, the cam surface 158 is still in engagement with the stem 90 of the valve 88 as shown in Fig. 6, but the cam surface 164 has engaged the pin 138 and closed the valve 122. The mixture of the two gases can now pass on to the inhaler but cannot pass into the gas bag. When the cam device is turned to bring the pointer into register with the mark *e*, the cam surface 158 70 has moved off the stem 90 so that the valve 88 closes. The cam surface 160, however, has moved into engagement with the stem 110 thus opening the valve 108 as shown in Fig. 7 so that nitrous oxide alone can pass to the inhaler. At the same time, the pin 138 is between the cam surfaces 162 and 164 so that communication with the gas bag is open. When the cam device is turned to bring the pointer into register with the mark *f*, the cam surface 160 is still in engagement with the stem 110 as shown in Fig. 8 but the cam surface 162 has engaged the pin 138 to close the valve 122 and shut off communication with the gas bag. Assuming now that the rotatable cam device is turned in the other direction to bring the pointer into register with the mark *b*, the cam surface 160 engages the stem 104 and opens the valve 102 as shown 80 in Fig. 9. Oxygen alone can now pass to the inhaler since the valves 88 and 108 are closed. At the same time, the pin 138 is between the cam surfaces 164 and 166 so that communication with the gas bag is open. If the cam device is now turned so as to bring the pointer into register with the mark *a*, the cam surface 160 still engages the stem 104, but the cam surface 166 has engaged the pin 138 so that communication with the gas bag is 85 shut off. This position corresponds to the 90 position shown in Fig. 8 except that the cam surfaces have been brought to the other side of the hollow member 86.

I claim:

1. An anæsthetizing apparatus having a mixing chamber, means for supplying thereto from independent sources of supply a plurality of gases under pressure, an inhaler, a hollow member interposed between said mixing chamber and said inhaler, a single rotatable cam device in said hollow member, a valve tensioned to close the passageway between said mixing chamber and hollow member, passageways connecting said sources of gas supply directly with said hollow member, valves tensioned to close said passageways respectively, said cam device having peripheral cam surfaces arranged to open separately any one of the aforesaid valves, a gas bag connected with said hollow member by a passageway, and a valve tensioned to open said last mentioned passageway, said cam device having end cam surfaces arranged to close said last mentioned valve and also to permit it to have an open position for the 100 105 110 115 120 125 130

open position of each of the aforesaid valves.

2. An anæsthetizing apparatus having a mixing chamber, means for supplying thereto from independent sources of supply two different gases under pressure, an inhaler, a hollow member interposed between said mixing chamber and said inhaler, a single rotatable cam device in said hollow member, a vertically disposed shank to which said cam device is secured and by which it may be rotated, a valve tensioned to close the passageway between said mixing chamber and said hollow member, a peripheral cam surface on the upper portion of said cam device for opening said valve, two passageways respectively connecting the sources of gas supply directly with said hollow member, two valves tensioned to close said passageways respectively, a second peripheral surface on said cam device below said first peripheral cam surface, said last mentioned cam surface being adapted to open separately either of said last mentioned valves when said first mentioned valve is in closed position, a gas bag connected with said hollow member by a passageway, a valve in said passageway normally tensioned into open position, and cam surfaces on the lower face of said cam device arranged to close said last mentioned valve and also to permit it to have an open position for the open position of each of the aforesaid valves.

In testimony whereof I hereunto affix my signature.

JAY A. HEIDBRINK.
